L. J. ODELL.
TYPE WRITING MACHINE.

No. 399,205.

Patented Mar. 5, 1889.

UNITED STATES PATENT OFFICE.

LEVI J. ODELL, OF BELOIT, ASSIGNOR OF THREE-FOURTHS TO JOHN E. BURTON, OF LAKE GENEVA, WISCONSIN, AND CHARLES H. ODELL, OF ROCKFORD, ILLINOIS.

TYPE-WRITING MACHINE.

SPECIFICATION forming part of Letters Patent No. 399,205, dated March 5, 1889.

Application filed May 16, 1887. Serial No. 238,388. (No model.)

To all whom it may concern:

Be it known that I, LEVI J. ODELL, a citizen of the United States, residing at Beloit, in the county of Rock and State of Wisconsin, have invented a new and useful Improvement in Type-Writing Machines, of which the following is a specification.

My invention relates to an improvement in type-writing machines; and it consists in the novel construction, arrangement, combination, and adaptation of the machine entire and of the several parts thereof, which will be more fully hereinafter described, and pointed out in the claim.

15 The object of my invention is to provide a type-writing machine which is simple and effective in its construction and operation, strong and durable, easily handled and readily understood, positive in its desired ultimate result, and cheaply manufactured. I attain this object by the mechanism illustrated in the accompanying drawings, wherein like letters of reference indicate corresponding parts in the several views, and in which—

25 Figure 1 is a perspective view of my improved type-writing machine. Fig. 2 is a top plan view of the same. Fig. 3 is a side elevation of the machine. Fig. 4 is a longitudinal vertical section thereof on the line xx of Fig. 30 1. Fig. 5 is a transverse vertical section on the line yy of Fig. 2.

A indicates the base-plate, formed of suitable configuration to render it applicable for the support of the several parts of the machine, and has two grooved strips, a' , secured to the top portion thereof, in which the carriage B is confined and has movement. Formed integrally with the strip a' is a short standard or post, A' , which is formed with an angular projection, A^2 , having a portion, A^x , bolted thereto and provided with two arms, a^2 , a^3 , pivotally secured to each side thereof, which project toward the forward portion of the machine and have the type-bar-supporting frame C cast therewith.

45 Inside of the arms a^2 , and integrally formed with the angular projection A^2 , are two stationary arms, a^3 , a^4 , which support the letter plate or strip D.

The carriage B is preferably rectangular in 50 form, and, as hereinbefore stated, is confined and has movement in the grooved strips a' , a' . Upon one side of this carriage B a ratchet-bar, b , is secured, the teeth of which project upwardly. Suitable projections are formed 55 with each end of the carriage-frame B, which project vertically up from the said plate and have the platen B' movably journaled therein. This platen B' consists of a circular rod covered with rubber, as in the ordinary form of 60 type-writing machine, and is revolved from one end by means of a thumb-wheel, D², which has a series of space-marks, b^3 , formed in its periphery. In one of the vertical supports b' a movable index, b^3 , is secured by means of a 65 rod passing therethrough, as shown in the drawings. This movable index b^3 is provided with a rod or pin, b^4 , which projects outwardly toward the thumb-wheel D², and when the said wheel is turned so as to bring the space- 70 mark thereon in a line with the said index-rod b^4 the space on the sheet of paper within the type-writer being operated upon will be caused to feed equally. This index-rod is arranged in the direct central line of the machine on the same line in which the typestrike 75 the sheet. The index is suitably mounted in a recess formed in the projection b' , and has a rod, b^5 , passing therethrough and forming a 80 pintle or pivot therefor, the said rod b^5 projecting from one side of the support b' and bent at an angle thereto.

To the side of the carriage opposite to that in which the index is situated a spring-retaining rod, B³, is secured, and projects along and 85 parallel with the platen, but slightly away therefrom, and its free end is adapted to be retained by the bent end of the wire b^5 , and when the paper surrounds the platen the said rod B³ acts to retain the said paper in a relative position thereto. To the side of the carriage B opposite that upon which the rack-bar b is secured the paper-guide B⁴ is attached at one end, the other end thereof curving under and partially up over the platen. By this 90 construction it will be seen that when the paper is inserted between the under side of the platen and the upper surface of the guide

B⁴ it may be readily fed over the said platen by turning the thumb-wheel B², and the rod B³ having been previously loosened from engagement with the wire b⁵ the end of the paper thus inserted is passed around the platen and under the rod B³, when the said rod is secured by the wire b⁵. When the paper will have been thus arranged, the machine will be in position for printing. On the rear end of 10 the carriage B a projection or stop, b⁶, is integrally formed, which is adapted to engage with a stud or screw-pin, b⁷, which is inserted through the bottom of a base rest or plate, A. This stud or pin b⁷ is arranged in such a position 15 that the carriage B will be permitted to be drawn backward to its full extent, but at the same time prevent the said carriage from becoming disengaged from the base-plate A and accidentally adjusted in such a position. 20 as to produce injury to the parts of the machine by striking where not desired. From the center of the projection A² a central guide, a⁵, is secured, which projects downwardly and over the platen in the central line 25 thereof and in the same line as the spacing-index arranged at the opposite end of the platen, and as hereinbefore described. This central index is in exact line of the printing, and shows the operator whether the machine 30 is printing straight or in a curved line and out of adjustment, so that the machine may be so adjusted to print in a straight line at all times.

To the rear portion of the grooved strip a', 35 adjacent to the post or standard A', a slotted ear, a⁶, is integrally formed therewith, which is engaged by a pawl, A³, by means of a projection, a⁷, which engages with the said slot in the ear a⁶. The said pawl A³ is formed 40 with the bend therein, which passes around the rear portion of the ear a⁶ and thence to a recessed angular projection, a⁸, formed integrally with the lever A⁴. The pawl A³ is pivoted to the lever A⁴ at this point, and engages 45 with the rack-bar b of the carriage B by means of a spur, a⁹, formed with the under side of the pawl A³, and regulates the feed of the said carriage, as will be more fully hereinafter set forth. The projection a⁷ by engaging the 50 slotted ear a⁶ limits the throw of said pawl A³ when the lever A⁴ is released.

The lever A⁴ is mounted to one side of the pawl A³ and is formed of such configuration as to project above the plane of the position 55 of the said pawl A³ and at an incline thereto. The lever A⁴ has a stop stud or pin, a¹⁰, upon its under side, which is adapted to engage with the top surface of the base-plate or rest A and limit the downward movement of the 60 said lever A⁴. The end of the lever A⁴ is provided with an angular projection, a⁸, to the one end of which the pawl A³ is secured, and the other end thereof passes down through an aperture in the base-plate and is secured to a fulcrumed projection, a¹¹, formed integrally with the upper portion of the projection a⁸ and adjacent to the end of the

pawl A³, with an eye, a¹², to which one end of a coiled spring, S, is secured, the other end of a coiled spring passing inside or adjacent to the standard A', and is secured to an eye formed integrally with the recessed strip a' at the other side of the said standard or post A'. When the lever A⁴ is pressed down, it draws against the coiled spring S, which, 70 through its resiliency, returns the lever to its normal position. When the lever A⁴ is pressed down, the pawl A³, pivotally secured thereto, is forced forward toward the front of the machine, and at the same time slightly raised, 75 when the spur formed in the under side thereof engages with another tooth of the rack-bar b, and upon the release of the lever A⁴ the said carriage B, supporting the rack-bar, is drawn under the printing-frame the distance 80 of one letter-space. When it is desired to return the carriage after a line of printing has been finished, and to begin a new line, the lever A⁴ is pressed down and the pawl A³ slightly raised by hand so as to disengage the 85 spur on its under side from contact with the rack-bar d, when the said carriage B may be returned or drawn back for the purpose of 90 starting a new line.

The type-bar-supporting frame C, held by 95 the arms a², is formed with closed sides and bottom portion, with the exception of a slight opening, c, therein, and with an open top. Grooves c' are also formed in the upper internal portion of the frame C, which is adapted 100 to engage the flanged top plate, C', of the type-bar C². This type-bar C² has movement transversely across the machine in either direction within the same frame, C, the type being arranged on the bottom portion thereof in a line 105 at right angles to the plane of the platen D and necessarily in a backward position.

On the top portion of the flanged plate C' a combined stylus and handle, C³, is secured, the point c² of the stylus projecting over the edge 110 of the plate and the printing-frame at one side, and the handle C⁴ projecting over the reverse side of the printing-bar-supporting frame.

To the under side of the opening c, formed 115 in the lower portion of the frame C, an inking device, E, is secured, and which consists of a circular roller or cylinder having a cloth wound around the same, saturated with the ordinary aniline printing-ink commonly used 120 upon type-writers. This cylinder E is supported by one end of a wire spring, S', which projects downwardly from a coil thereof, which is secured on each side of the frame C upon suitable projecting studs or pins e, and 125 retained upon said studs or pins by projections c⁵, formed integrally with the side of the frame C. The other end of the spring S' projects downwardly from the central stud or pin upon which it is supported, and in like 130 manner incloses and retains a second inking device or cylinder, E², which is of the same construction as the cylinder E, heretofore described. As the type-bar C² is moved trans-

versely backward and forth in the frame C, the type engage with the inking-cylinders E and E² and become inked. Every movement of the said bar E² brings the type on the under face thereof in contact with these inking-rollers, and it will be seen that the said bar is supplied with ink at all times. From the under side of the frame C a short arm, c⁶, projects downwardly, and adapted to engage with the lever A⁴, and depress the same, so as to move the pawl A³ back one tooth on the rack, and as the frame C moves upward the spring S operates to move the pawl A³ to its first position, carrying the paper-carriage with it to the extent of one space.

The recessed or apertured letter-plate D, supported by the arms a³, is formed with a recess in its upper face, in which a strip, D', of paper, brass, or other material containing the letters of the alphabet and other necessary characters may be secured by suitable means. The letters and characters may be inscribed on the plate. On the edge below this letter-strip D' a series of recesses are formed which are engaged by the stylus c³, hereinbefore described. These recesses d are arranged in a direct line with the letters or figures or other characters on the strip D', and when the stylus is caused to engage with any one of the said recesses the type-bar C² will cause an impression to be made on the paper of the same letter with which the stylus is in engagement. This is due to the fact that when the stylus is moved to engage with the letters represented by the recesses d the type-bar C² has the letters arranged in exactly the same position as those upon the strip D'.

To one side of the standard A' a spring, S², is secured, having a finger, s, which projects under and engages with the frame C, and is adapted to keep the said frame in a raised position, as shown in Fig. 3.

It will be observed that the two rollers E and E² are arranged in such a manner as not to engage with the surface of the paper or the platen B when the frame C is depressed.

When the paper has been inserted around the platen and the carriage B has been drawn back toward the operator, the machine is ready for printing. When the frame C, carrying the type-bar C², is depressed against the resisting action of the spring S², an impression is caused upon the surface of the paper, being a letter or figure in position with

the recess with which the stylus has engaged. When the said frame C is depressed, the projection c⁶ thereof strikes the top of the lever A⁴, which, acting upon the pawl A³, as hereinbefore set forth, carries the latter through its spring-connection to feed the carriage B one space forward, and adjusts the paper or the said carriage for the impression of the following letter. This operation is continued until the whole line is printed and the carriage B drawn backward, as hereinbefore set forth.

It will be seen that the carriage B travels in a plane at right angles to the plane of the position of the type-bar, and that the said carriage intermittently passes away from the operator, and when returned to begin a new line is drawn back toward the said operator.

Any size, style, or shape of type may be used and formed with the type-bar, when the several parts of the machine may be modified and readjusted, as may be desired.

The novelty, utility, adaptability, and practicability of my improved type-writing machine being obviously apparent, it is unnecessary to further enlarge upon the same herein.

It is obvious that many minor changes in the construction and arrangement of the several parts may be used and substituted for those shown and described without in the least departing from the nature and principle of my invention.

Having thus described my invention, I claim—

In a type-writing machine, the base A, the carriage B, having the rack-bar, and the vibrating type-bar frame C, having the depending rigid arm C⁶, combined with the spring-actuated lever A⁴, carrying a pawl to engage the rack-bar of the carriage, said lever being pivoted to the base and arranged below and on a line with the arm C⁶, so that upon depression of the type-bar frame the arm C⁶ comes in contact with the lever A⁴, the latter being extended upward and outward, whereby it is within convenient reach to be struck by the hand of the operator in spacing, as set forth.

In testimony that I claim the foregoing as my own I have hereto affixed my signature in presence of two witnesses.

LEVI J. ODELL.
